CANVAS BUTTER FOR BINDERS.

1,138,987.

Specification of Letters Patent.

Patented May 11, 1915.

Application filed November 29, 1912. Serial No. 734,090.

To all whom it may concern:

Be it known that I, HAROLD T. SMITH, a citizen of the United States, residing at Willis, in the county of Brown and State of

5 Kansas, have invented certain new and useful Improvements in Canvas Butters for Binders; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 My invention relates to a butter for grain harvesters, and has for its principal object to provide a simple and efficient device for evening grain delivered from an elevator onto a binding table, so that the stalks may 20 reach the binder in proper position. In accomplishing this object I have provided the improved details of structure herein-after described and illustrated in the accompanying drawings, wherein:—

25 Figure I is a perspective view of portions of a harvester, particularly illustrating the upper portion of the binding table and my improved butter. Fig. II is an inverted perspective showing a driving mechanism for 30 actuating the butter. Fig. III is a detail perspective of the butter. Fig. IV is a longitudinal vertical section of same, showing part of the binder table.

Referring more in detail to the parts:—

35 1 designates a portion of the frame of a harvester of any ordinary construction comprising a traction drive wheel 2, elevator frame 3 and the usual elevator 4, which latter preferably comprises the double aprons 40 5, one of which is run over a shaft 6 in the upper portion of the frame 3 and driven from a chain belt 7 which receives its power from a shaft 8 connected through suitable gearing with the traction drive wheel 2.

45 Converging upwardly toward the elevator frame 3 is the binder table 9, which also may be of any ordinary construction, the binding mechanism not being shown as it forms no part of the present invention.

50 The butter, which forms the subject matter of this application, comprises spaced top and bottom frame boards 10, of substantially triangular construction, the bases of which face forwardly relative to the har- 55 vester and the bottom board being fixed

rigidly to the binding table. The upper inner side 11 of each board 10 is comparatively short and converges into the apex 12 near the upper portion of the binding table. The boards 10 are spaced by the axles 13, 60 one of which is arranged at each corner of the board, and each of the axles carries a roller 14 over which a slatted apron 15 is adapted to travel when a driven roller is actuated. The rollers 14 are set in from the edges of the frame boards so that the apron travels wholly therebetween and the apron slats bear against the inner surface of the boards. One of the axles, preferably that at the lower end of the butter, is slidably 65 mounted in slots 16 in the boards 10 and yieldingly tensioned outwardly to tighten the apron by means of a yoke 18, the arms of which inclose the ends of the axle and the base of which carries a pin 19 which projects through a cross-bar 20 carried by the frame boards, and has a spring 21 surrounding same and bearing against the base of the yoke and the bar to act as an ordinary belt tightener. The upper axle 13 extends through the binding table and carries a beveled gear wheel 22 which meshes with a similar wheel 23 on a shaft 24 journaled in the under side of the binding table and provided with a sprocket wheel 25 80 which is connected with a sprocket wheel 26 on the elevator apron shaft by means of a chain 27 so that when the elevator is in operation the butter is driven through the 85 gearing described.

In using the device, the harvester is driven through the grain which is cut, carried up the elevator and delivered to the binding table in the ordinary manner. Owing to the fact that the head of the 95 grain is heavier than the stalk butts, the headed ends will, when delivered onto the binding table, fall faster than the butt ends, so that the stalks descend at an incline unless means is provided for straightening 100 same.

With the binding table provided with my improvement, when the grain is delivered onto the table and the head ends descended in advance of the butt ends, the butt ends are caught by the butter apron so that the stalks are moved laterally across the binding table and the bottom ends advanced to even the stalks before the latter reach the binding mechanism.

With a butter of this character, there is no tendency to strike the grain so that the stalks will be "kicked" from the table, and the action is positive, as all of the grain 5 must pass the butter to get to the binding mechanism.

Having thus described my invention, what I claim as new therein and desire to secure by Letters-Patent, is:—

- 10 1. The combination with a binding table, of a butter comprising closed triangular and parallel frame members having longitudinal slots therein adjacent one of their apices, having apices directed inwardly over the table, and having short, inwardly directed sides at their upper ends, a yoke 15 slidably mounted between the frame members, a roller having a shaft mounted in the yoke and projected into the frame slots, 20 rollers revolvably mounted in the other apices of the frame members, and an apron run over said rollers.

2. The combination with a binder table,

of a butter comprising closed triangular and parallel frame members having longitudinal slots therein adjacent one of their apices, having apices directed inwardly over the table, and having short, inwardly directed sides at their upper ends, a yoke 25 slidably mounted between the frame members, a roller having a shaft mounted in the yoke and projected into the frame slots, an apertured bar for spacing said frame members, a rod on said yoke slidably projected through the aperture in said bar, a spring 30 surrounding the rod and bearing against the bar and yoke, rollers revolvably mounted in the other apices of the frame members, and an apron run over said rollers in close proximity to said frame members. 40

In testimony whereof I affix my signature in presence of two witnesses.

HAROLD T. SMITH.
